UNITED STATES PATENT OFFICE.

EDWARD TOWN AND JAMES L. CHICHESTER, OF BUFFALO, NEW YORK.

PAPER-RULING MACHINE.

Specification forming part of Letters Patent No. 42,418, dated April 19, 1864.

To all whom it may concern:

Be it known that we, EDWARD TOWN and JAMES L. CHICHESTER, both of Buffalo, in the county of Erie, in the State of New York, have invented a new and useful Improvement on Machines for Ruling Paper; and we do hereby declare that the following is a full, clear, and exact description of the construction and operation of the same, reference being had to the annexed drawings, making part of this specification, in which—

Figure 1 is a side elevation. Fig. 2 is a plan view. Figs. 3 and 3b are sectional elevations showing the gaging device, (except the side gage,) with its cams, levers, and connections in two positions, viewed from the back side of the machine; and Fig. 4 is a side view of one pair of the strikers and an end view of the same in position on the striker-wheel K.

The same letters of reference refer to the same parts of the machine in all the drawings.

The general form and construction of the principal parts of this machine are the same as in all ruling-machines in common use, and there are many necessary appendages and conveniences used in this machine in common with others which are not represented in the drawings accompanying this specification, such parts only being represented as are necessary to a full and clear understanding of the nature and operation of our invention.

The principles of the common ruling-machine and their application to both single and double machines, whether moved by hand, steam, or other power, are well known and need not be described here. It is also well known that these machines, though efficient and all that may be desired for the class of work technically called "faint-lining," are inefficient and so defective that the double machine cannot be used for any of the class of work technically termed "down-lining" or "striking," these terms referring to all that class of work which requires one or more blank spaces on the sheet for the purpose of writing headings or other purposes. With this explanation we now state that the object or design of this invention is to produce a machine on which we can do any and all kinds of down-lining, whatever may be the pattern or number of headings required, and use the machine for this purpose either in its single or double

form, and drive or move it, as may be desired, either by hand, steam, or other power, the mechanism being so arranged that it may be adjusted to "strike" accurately any given pattern by automatic action.

Having thus stated the nature and design of our invention, we now proceed to describe its construction and operation as follows.

A is the frame of the machine.

B and C are the two main cylinders. The main apron D, on which the paper is carried through the machine, is driven by the cylinder B and a set of binding-lines; a, designed to hold the paper on the apron and secure its motion or movement with it, are driven by the cylinder C. These two cylinders are of equal diameter, and are geared together so as to move with equal speed, and the crank or pulley, according as the machine is to be driven by hand or other power, is affixed to the shaft of either one of these cylinders, as may be most convenient.

The pen-beam E is constructed and fixed in the machine in the usual manner, and the pens b are fixed in the beam in the same manner, and are constructed and used in all respects as on the common machines. Thus we have described the parts of the common ruling-machine, which are so connected with our invention as to render their description necessary to a full and clear understanding of the same, which invention, we will here state, consists of two distinct mechanical combinations, which are so connected, and their action and usefulness are so dependent each upon the other that they in fact constitute but one invention.

For the purpose of more accurate description, we will designate one of the combinations above mentioned as the gaging device; which device, as shown in the drawings, consists of the side gage, G; the reciprocating or vibrating roller e, the chased or grooved roller d, the spring-plate e, the fingers ff, and the finger-shaft H; and the other combination we will designate the "striking device," which consists of the double slide or sliding frame I, the stud g, the swinging lever h; the spring-catch k, the strikers ll, and the striker-wheel K, and all the different parts of both of the combinations above named are moved or actuated as specified, and for the purposes set forth, as follows:

The shaft F is geared with the cylinder B, to secure a uniform relative rate of speed between the shaft and cylinder, and upon this shaft are fixed in proper positions the striker-wheel K, and the three cams, marked in the drawings, respectively, *m*, *o*, and *p*, by which wheel and cams all the parts of both the combinations above named are actuated. By this arrangement a connection and unison of action is obtained throughout all the working parts of the machine, including those parts in common use, together with those which constitute our invention, this connection or unison of action being the necessary condition to the successful accomplishment of our design in this invention.

We now explain the use of each part of the above-named combinations, which explanation, with reference to the drawings, will constitute a sufficient description of their construction and operation in detail.

The side gage, G, is used to press upon the side of the sheet of paper while it rests against the fingers, to bring each sheet to a given point on the machine to secure a uniform margin. The construction of this gage is shown in the drawings, Fig. 1 and 2, and its movements are effected by the action of the helical spring on its shaft and the cam *m* on the shaft F.

The roller *c* carries one end of the feed-apron Q, and it has a slight reciprocating motion from and to the grooved roller *d*, for the purpose of permitting the sheets of paper to lie free and unbound between said rollers while resting upon the fingers and being placed in position by the side gage, and to bind or press the sheets against the roller *d* at the instant the fingers rise and liberate it, the object of this being to secure the starting of the sheet at this exact point in the run of the machine. To effect this motion the roller *c* is hung on a rock-shaft, and an arm extends from the shaft to the cam *p*, as shown in the drawings, Figs. 3 and 3^b, which cam is so formed as to give it the desired movement.

The chased or grooved roller *d* is used to hold the binding-lines *a* in position, as required, which lines pass from the cylinder C over this roller and back to the cylinder under it, to hold the edge of the paper straight while it rests on the spring-plate *e*, and also to prevent the edge of the paper from rising with the fingers when they rise to liberate it.

The spring-plate *e* is a sheet of thin metal or other suitable material affixed to the rock-shaft, and it should be long enough to extend the whole width of any sheets of paper to be ruled on the machine. It may be fixed on the shaft in any convenient way, being fastened on the side next to the roller *c*, so that the face of the plate will be sufficiently below the upper side of the roller to allow the paper to pass over it without catching, and as near to the roller as possible, allowing for the free passage of the feed apron Q. The other edge of the plate is raised a little from the shaft or

board to which it is attached, so as to act freely as a spring and be in position to just touch the lines *a* as they pass from the roller *d* to the cylinder, and thus hold the edge of the paper straight and secure its certain contact with the fingers at the proper point. Whatever is used for this purpose must necessarily have the yielding qualities of a spring, for the reason that after the head of the sheet has passed the fingers and has entered between the cylinders the fingers are brought down again to catch and properly gage the incoming sheet before the first-named sheet has completely left their range, and if any unyielding substance was in the place of the plate *e* the sheet would be bound between it and the fingers and prevented from passing into the machine; but this plate yields under the paper as the fingers press upon it sufficiently to allow the sheet to pass freely on. The fingers *f f* are formed as shown in the drawings, Figs. 1 and 2, having set-screws to secure them in position when properly placed on the shaft, and are used to catch and hold the sheets of paper as they come successively into the machine, until the machine comes to the proper point with reference to the striking device, to secure their meeting the pens properly to receive the pattern to be ruled upon them, and the shaft H is designed to hold and operate the fingers as required, motion being communicated to it by the cam *o*, as shown in the drawings, Fig. 3 and Fig. 3^b. We will here state that though only two of these fingers are here represented, a greater number may be required for some kinds of work, and therefore the working-machines are provided with four or more, as may be required, all being formed and placed on the shaft in the same manner as those represented.

The sliding frame or double slide I is constructed as shown in the drawings, Fig. 1, and is designed to communicate motion to the pen-beam E. The use of the upper sliding piece is to connect the pen-beam with the frame I, which is done by swinging the stud *g* down till it strikes against a shoulder on the slide, where it is held in position by the hooked spring, as shown, and the screw thread and nuts on the end of this slide are used to give the pens their proper bearing on the sheet, which is done by turning the nuts, and thereby setting the slide forward or back, as may be required for this purpose. When it is desired to run the machine without operating the pens, the brace, which is hinged to the spring, is placed with its foot in the notch on the end of the slide, and the spring is held off from the stud *g*, and the slide moves freely without connection with the pen-beam. The lower slide of this device I has an arm attached to it, which passes through a plate attached to the frame, and connects with the lever *h*, the plate being slotted as required, to allow the arm to pass and to stop it at each end of its movement. There are two notches in the side of this slide which receive the

UNITED STATES PATENT OFFICE.

EDWARD TOWN AND JAMES L. CHICHESTER, OF BUFFALO, NEW YORK.

PAPER-RULING MACHINE.

Specification forming part of Letters Patent No. 42,418, dated April 19, 1864.

To all whom it may concern:

Be it known that we, EDWARD TOWN and JAMES L. CHICHESTER, both of Buffalo, in the county of Erie, in the State of New York, have invented a new and useful Improvement on Machines for Ruling Paper; and we do hereby declare that the following is a full, clear, and exact description of the construction and operation of the same, reference being had to the annexed drawings, making part of this specification, in which—

Figure 1 is a side elevation. Fig. 2 is a plan view. Figs. 3 and 3b are sectional elevations showing the gaging device, (except the side gage,) with its cams, levers, and connections in two positions, viewed from the back side of the machine; and Fig. 4 is a side view of one pair of the strikers and an end view of the same in position on the striker-wheel K.

The same letters of reference refer to the same parts of the machine in all the drawings.

The general form and construction of the principal parts of this machine are the same as in all ruling-machines in common use, and there are many necessary appendages and conveniences used in this machine in common with others which are not represented in the drawings accompanying this specification, such parts only being represented as are necessary to a full and clear understanding of the nature and operation of our invention.

The principles of the common ruling-machine and their application to both single and double machines, whether moved by hand, steam, or other power, are well known and need not be described here. It is also well known that these machines, though efficient and all that may be desired for the class of work technically called "faint-lining," are inefficient and so defective that the double machine cannot be used for any of the class of work technically termed "down-lining" or "striking," these terms referring to all that class of work which requires one or more blank spaces on the sheet for the purpose of writing headings or other purposes. With this explanation we now state that the object or design of this invention is to produce a machine on which we can do any and all kinds of down-lining, whatever may be the pattern or number of headings required, and use the machine for this purpose either in its single or double

form, and drive or move it, as may be desired, either by hand, steam, or other power, the mechanism being so arranged that it may be adjusted to "strike" accurately any given pattern by automatic action.

Having thus stated the nature and design of our invention, we now proceed to describe its construction and operation as follows.

A is the frame of the machine.

B and C are the two main cylinders. The main apron D, on which the paper is carried through the machine, is driven by the cylinder B and a set of binding lines; a, designed to hold the paper on the apron and secure its motion or movement with it, are driven by the cylinder C. These two cylinders are of equal diameter, and are geared together so as to move with equal speed, and the crank or pulley, according as the machine is to be driven by hand or other power, is affixed to the shaft of either one of these cylinders, as may be most convenient.

The pen-beam E is constructed and fixed in the machine in the usual manner, and the pens b are fixed in the beam in the same manner, and are constructed and used in all respects as on the common machines. Thus we have described the parts of the common ruling-machine, which are so connected with our invention as to render their description necessary to a full and clear understanding of the same, which invention, we will here state, consists of two distinct mechanical combinations, which are so connected, and their action and usefulness are so dependent each upon the other that they in fact constitute but one invention.

For the purpose of more accurate description, we will designate one of the combinations above mentioned as the gaging device, which device, as shown in the drawings, consists of the side gage, G; the reciprocating or vibrating roller c, the chased or grooved roller d, the spring-plate e, the fingers ff, and the finger-shaft H; and the other combination we will designate the "striking device," which consists of the double slide or sliding frame I, the stud y, the swinging lever h; the spring-catch k, the strikers l l, and the striker-wheel K, and all the different parts of both of the combinations above named are moved or actuated as specified, and for the purposes set forth, as follows:
